APPARATUS FOR MANUFACTURING LIGHT
WEIGHT BUILDING BOARDS
Gerrit Jan van Elten, Tromplaan 1,
Voorthuizen, Netherlands
Filed Jan. 28, 1964, Ser. No. 340,654
Claims priority, application Germany, Jan. 30, 1963,
E 24,255
9 Claims. (Cl. 18—4)

The present invention is related to an apparatus for manufacturing light weight building boards, and more particularly to stacking and pressing light weight building boards of wood wool mixed with a binding agent.

Light weight building boards of the type described are manufactured by mixing wood wool and binding agent, such as cement, and filling the mixture into moulds. The moulds are arranged in contiguity with one another, and at their joining points, the wood wool mixture is cut into pieces of boards. The moulds, each containing a board, are piled up, compressed in a press and stored under pressure until the setting of the cement is completed.

The longitudinal edges of the moulds are provided with side rims, which may be rigidly fastened to the moulds, movably mounted on the moulds or laid against the moulds in loose connection. The conventional pressing devices in use for these moulds have shown to be disadvantageous as the side rims, when the mould is introduced into the press, may easily be damaged by the press power, or, where the loose rims are applied, a burr may occur between the rim and bottom of mould. This impairs the quality of the building board and makes it necessary to remove the burrs in a separate working process, involving cost and labor.

It is an important object of the invention to provide apparatus by which the moulds enclosing the light weight building boards are introduced into and piled up inside the press in such a manner that damage or wear of the side rims is avoided.

A further object is to provide apparatus in which formation of burrs, at the longitudinal edges of the building boards, piled up and compressed in the press, is eliminated.

Another object is to supply an apparatus by which the method according to the invention can be carried out.

Further objects and advantages will become apparent from the following description of two exemplary embodiments of the apparatus according to the invention, which are shown in the drawing.

In the drawing, which is a simplified presentation,

FIG. 1 is an end view illustrating a press for moulds of rigid side rims in accordance with the instant invention and in the position of introduction of a new mould;

FIG. 2 is an enlarged view of the lower part of the press of FIG. 1 showing a new mould being introduced;

FIG. 3 is an enlarged view of the lower part of the press as in FIG. 2 but showing another stage of operation;

FIG. 4 is an end view of a press for moulds of loose side rims in accordance with the instant invention and in the position of introduction of a new mould;

FIG. 5 is an enlarged partial view of FIG. 4 of a part of the apparatus of FIG. 4 but in another stage of operation;

FIG. 6 is an enlarged partial view of the press of FIG. 4 in a stage of operation subsequent to the stage shown in FIG. 4;

FIG. 7 is an end view of the press of FIG. 4 showing the press subsequent to completion of elevation of the mould.

In the apparatus of the instant invention the moulds, piled up inside the press, are supported on steel plates

2

which extend underneath the longitudinal edges of the bottom plate of the lowest mould. As a new mould is moved into position to be added to the bottom of the pile, the new mould is raised so that its rims are adjacent the steel plates. The steel plates are then withdrawn and the new mould and the moulds previously piled one on the other in the process are lifted to an elevated position just above the steel plates. The steel plates are then returned to their initial position, in which they carry the complete pile of moulds.

Where the rims are fastened to the bottom plate of the mould, the steel plates, after the newly arrived mould is raised, are moved inwardly toward each other and the center of the mould, and thereby push back into the mould any material extending over the top surface of the rim of the newly arrived mould. This procedure eliminates any burrs at the longitudinal edges of the finished boards. Where loose rims are used on the moulds, the rims are advanced between steel plates, and a horizontal guide surface of the press structure. The rims are only advanced for part of their width before the new mould is raised sufficiently to position its bottom plate adjacent the lower surface of the rim. The rims are then pushed onto the bottom plate of the mould and compress the material on the bottom plate from both sides. Subsequent thereto, the steel plates are withdrawn from under the rims and an upwardly directed pressure is exerted on the bottom plate of the new mould.

In both cases, the weight of the pile of moulds in the press is carried by the two lateral steel plates which not only support the pile of moulds but also eliminate burrs at the longitudinal edges of the boards so that subsequent work to remove burrs is unnecessary.

Where loose rims are used the invention is of particular advantage in that the rims can be moved laterally onto the mould without being subjected to the weight of the pile of moulds. The power of motion required to move the rims is reduced and the rims are protected from wear. The force for raising the mould against its rims may be varied and, preferably, is adjusted in such a manner that the rims are free from play when moved towards the inside of the press between the steel plates. The absence of play insures that burrs will not form.

In carrying out the invention with moulds having rigid side rims, the invention, according to a preferential embodiment, provides a device containing a steel plate at either side of the press, which is rested on a horizontal supporting surface and is connected by an articulated connection to a driving or moving mechanism. Due to the articulated connection, the steel plates can be freely suspended and are, in their raised position, under like pressure from above and below. The steel plates have a certain freedom which allows them to precisely adjust to the bottom plates of the moulds, no matter whether these are straight or slightly crooked.

The steel plates should be linked, through a switching device controlling their movement, to the drive of the press-table for receiving and lifting newly arrived moulds. The steel plates and press-table are preferably operated by pressure force and, with an automatic control of the drives, the compressing procedure may be carried out without any operating staff. This applies to moulds of both rigid and loose side rims and in the latter case, the rims may be supplied from a magazine and automatically conveyed to the moulds.

The invention will be best understood by reference to the accompanying drawings in which like parts bear the same reference numerals throughout the figures.

In the embodiment of FIGURES 1 to 3, a plurality of finished compressed moulds 12 are piled up inside press 11, the bottom plates 13 of each mould having side rims 14 fastened to the plate. The moulds 12 are piled up on

top of one another under the charge of a press ram 15, which is linked with a pressing device 16. In lieu of press ram 15, a weighty concrete plate or similar charging element may be used.

Two steel plates 17 are provided to support the piled up moulds 12 along their longitudinal edges. The plates 17 rest on horizontal frames 18 of the press structure and, through longitudinal joints 19, are linked with the piston rods of hydraulic cylinders 20, the latter being fastened to part 22 of the press structure by means of vertical joints 21. The number of hydraulic cylinders 20 to be employed depends on the length of the building boards to be manufactured. Considering the more frequently used lengths of boards, either side of press 11 receives two or three hydraulic cylinders 20.

Attached to the side of each of the frames 18 is an electric switch 23 having a spring pressed switching bolt 24 held by the spring in contact with steel plate 17. Switch 23, in a manner later to be described, controls hydraulic driving cylinder 25 of press-table 26, positioned under press 11. Press table 26 is movable by cylinder 25 in a vertical direction.

The moulds 12 are, in a filling machine as described in my Patent No. 3,096,227, filled with moistened wood wool mixed up with a binding agent, such as cement, and receive a rough pressing in the filling machine. Due to its elasticity, the material of the building boards re-expands on leaving the filling machine so that it projects above the two side rims 14 fastened to bottom plate 13, as can be seen from FIG. 1.

Subsequent to their preparatory treatment in the filling machine, moulds 12 are conveyed onto press-table 26, for example by means of a roller way 27. The moulds can reach press-table 26 without difficulty as the other moulds piled up within press 11, in the position shown in FIG. 1, are carried by the steel plates 17.

When the pressing procedure starts, press-table 26 is, by means of hydraulic cylinder 25, raised sufficiently to bring the rigid rims 14 of bottom plate 13 of mould 12 on press 26 into contact with the bottom surfaces of steel plates 17 and raises plates 17 and moulds 12, in press 11, from their initial horizontal position of FIG. 1 to a slightly elevated horizontal position. The slight elevation of plates 17 is possible because of the horizontal and vertical joints 19 and 21.

In this elevated horizontal position, steel plate 17 is spaced from bolt 24 of switch 23, as is shown in FIG. 2, stopping driving cylinder 25 of press-table 26. At the same time, switching bolt 24 operates hydraulic cylinders 20, to move steel plates 17 in an inward direction and push back burr 28, formed in the space between side rim 14 and bottom plate 13 of the undermost mould inside the press because the material of the building board was slightly compressed and some of the material pressed over the edge of rim 14 as the new mould on press-table 26 was elevated. Because of the hydraulic cylinders 20 being in articulated link with parts 22 of the press structure, and the vertical forces on the plates are balanced, the steel plates 17 are under like pressure from above and below.

On reaching the position shown in FIG. 3 and after pushing burr 28 back into the hollow of the mould, the steel plates 17 are retracted from the rims 14, and press-table 26 is further elevated by supplying additional pressure energy to driving cylinder 25 until the bottom plate 13 of the lowermost mould is moved into position above the level of steel plates 17. The material of the building board in the lowermost mould is compressed to the height of rims 14 and at the same time the whole pile of moulds is raised by the height of one mould. After this, the steel plates 17 are returned into their initial position of FIG. 1 below bottom plate 13 of the mould just raised on press-table 26. Press-table 26 is lowered and the whole pile of moulds rests on steel plates 17. Press-table 26 is further

lowered into its initial position of FIG. 1 to accept another mould.

The moulds piled up in press 11 are under the charge of press ram 15 and pressing device 16. Pressing device 16 may be of a double acting type operated by hydraulic force. The pressure exercised by pressing device 16 should be regulated so that the presence can be decreased when the pile of moulds inside press 11 is increased. In a simplified modification, press ram 15 is replaced by a weighty plate, and pressing device 16 is of the single acting type.

After the compressing procedure, the pile of moulds is put aside while the binding agent is setting, during which time the moulds are kept together by clamps or again charged with a weighty plate of concrete, or the like, so that the material of the building boards cannot expand.

The apparatus of the invention is not restricted to moulds with rigid rims. It is equally advantageous in cases where the side rims are slidably mounted upon the moulds. This can be accomplished by holding the rims by bolts and providing slots in the rims or moulds for limited movement of the rims (not shown). Finally, the rims may be placed without any connection upon the edges of the moulds (not shown). Furthermore the rims can be placed upon the moulds only during the process of compression. In this case, the filling machine is provided with an additional device by which the raw material filled into the moulds is restricted to the size of the latter.

An exemplary embodiment of an apparatus designed for compressing moulds of loose side rims is in its various stages of operation shown in FIGURES 4 to 7.

In this apparatus, the moulds 12 piled up on top of one another in press 11 under the charge of the press ram or weighty plate 15, are rested on the two steel plates 17, connected to driving cylinders 20 through an interposed magazine box 30 containing loose side rims 31. Magazine box 30 is mounted on a U-shaped iron rail 32, which exceeds the length of side rims 31, and at its end portions rail 32 is supported on the press structure. A plurality of horizontal joints 33, coupled with the piston rods of hydraulic cylinders 20, is located at the outside wall of magazine box 30. By means of their respective vertical joints 21, the hydraulic cylinders 20 are fastened to part 22 of the press structure in the same manner as in the embodiment shown in FIG. 1. Below magazine box 30, a plurality of hydraulic cylinders 34 are arranged at either side of the press. The piston rods of cylinders 34 carry a slide 35, guided on a horizontal surface 36 below box 30. The surface 36 is adjustable in its height in order that side rims of varied sizes may be fed into the press.

Press-table 26, together with its hydraulic driving cylinder 25, is arranged below press 11 in the same manner as in the first embodiment shown in FIG. 1 with bearings 37 for conveyor wheels or chains 38, on which the moulds coming from the filling machine are supplied to press-table 26.

Referring now to the manner in which the apparatus is operated, the mould coming from the filling machine is at first put on press-table 26. The pile of compressed moulds inside press 11 rests on the two steel plates 17, which are fully advanced into position under the lowermost mould in the press. From the magazine boxes 30 at either side of the press, a rim 31 has been moved partly below steel plates 17 by slide 35 of piston rod 34. The position of rims 31 at this stage is shown in FIG. 4. By supply of pressure energy to hydraulic cylinder 25, press-table 26 is raised sufficiently to slightly press bottom plate 13 of the new mould against the two rims 31, which are then advanced into their final position on the mould by actuating hydraulic cylinder 34, whereby the material of the building board on the mould is compressed from both sides into the size intended. There is hardly any vertical pressure straining the rims 31 while being advanced, as the weight of the pile of

moulds and the pressure of press ram 15 are absorbed by the steel plates 17. This enables long useful life of the rims so that their height and strength after long periods of usage are still much the same as in the beginning.

Subsequent to the advancement of the rims 31, both the steel plates 17 are withdrawn from position under the bottom plate 13 of the lowermost mould in the press to the position shown in FIG. 6. Thereafter, slide 35 is retracted, opening magazine box 30 to supply the next rim 31 to the horizontal surface 36. Press-table 26 is now further elevated until the rims 31 touch the bottom plate 13 of the lowermost mould of the pile in press 11. The material of the building board in the mould on press-table 26 is then compressed to the height of rims 31. At the same time, the whole pile of moulds in press 11 is raised by the height of one mould so that the bottom plate of the now lowermost mould in press 11 is situated above the level of the two steel plates 17, as shown in FIG. 7. The steel plates 17 are then returned from their retracted position of FIG. 6 to position under the bottom of the now lowermost mould, as shown in FIG. 7. New rims 31, from magazine box 30, fall onto the horizontal surface 36. Finally, press-table 26 is lowered and the pile of moulds rests on the steel plates 17 so that the next mould may be moved in from the filling machine.

By regulating the supply of energy to hydraulic cylinder 25, the pressure used for raising the moulds can be varied according to the force needed for compression of the boards, which depends on the board thickness: thin boards require more pressing power than thick ones.

If a pressing power of 300 kilograms is required to compress the material of the building board to its wanted thickness, the pressing power of press-table 26 should be adjusted to 400 kilograms. The pressure exerted on either rim 31 will in this case amount to only 50 kilograms as, owing to the interposition of the steel plates 17, the rims are relieved from the load of the pile of moulds and of press ram or weight 15. If the steel plates 17 were omitted, either rim 31 would be subject to a pressure of 750 kilograms; namely, 400 kilograms, which is one half of the weight of the piled up moulds and 500 kilograms which is one half of the weight 15, minus the counter-pressure of 300 kilograms of the material. Considering these figures, it is apparent that the steel plates provided by the invention essentially relieve the side rims from pressure. Because of this and of the guidance of the upper surface of side rims 31 at the steel plates 17, the upper surface of side rims 31 are not subject to any wear and tear. Although the lower surface of the rims is subject to some wear, this amounts to only 50/750 of the wear in conventional construction, and is therefore negligible. Further, the material of the building board is compressed without forming a burr so that subsequent removal of the burr and the loss of raw material connected with it are eliminated.

The supply of the loose side rims 31 may be performed under automatic control, through automatic control of hydraulic cylinders 34, by which the rims are pushed in, by a switching device similar to the embodiment of FIGURES 1 to 3.

It is a particular advantage of the invention that the same apparatus may be used both for moulds of rigid and of loose side rims. To perform this, the steel plates 17, with their rails 32 and magazine box 30, may be mounted in the same freely pending way as the embodiment of FIGURES 1 to 3. Alternatively, the apparatus of FIGURES 4 to 7 may be used for moulds of rigid rims without being altered.

Another modification may be made with respect to the steel plates 17. Steel plates 17 may be guided on a surface adjustable in its height in place of the rigid frame 18 of the press structure, to make plates 17 adjustable to boards of varied thickness. In a preferential embodiment, the adjustable guiding surface is placed in an initial horizontal position from which it is moved downwards.

In still another variation, the steel plates 17 themselves may be adjustable in their vertical position if the guiding surfaces are rigidly fastened to the press structure.

While I have chosen to illustrate my invention by showing and describing preferred embodiments of it, I have done so by way of example, as there are other modifications and adaptations which can be made by those skilled in the art and which are fully within the scope of my claims, which are:

1. In the manufacture of light weight building boards, an apparatus for treating a wood wool-binder mixture carried upon bottom plates of a stack of moulds, said apparatus comprising two opposed plates for engaging opposed bottom edges of the lowermost mould of said stack, means swingably supporting said opposed plates, first hydraulic means connected with said swingable means for moving said opposed plates toward and away from each other, a press table located below said opposed plates, means carried by said press table for receiving an additional mould, second hydraulic means connected to said press table for actuating said press table and said mould receiving means for moving said additional mould into engagement with the lowermost mould of said stack, an adjustable pressing device located above said opposed plates for engaging the uppermost mould of said stack, means connected with and actuating said first and second hydraulic means for moving said additional mould into place of said lowermost mould and for compressing the wood wool-binder mixture in said additional mould against the bottom of said lowermost mould and means movable in a horizontal direction towards each other for pushing pressed mixture projecting horizontally outward on said additional mould into said mould.

2. An apparatus in accordance with claim 1, wherein said moulds comprise rims fixed to opposed edges of the bottom plates, said opposed plates being movable between the rims of the additional mould and the bottom plate of the lowermost mould.

3. An apparatus in accordance with claim 1, having loose rims, means for placing two rims upon opposed edges of the additional mould, and means for feeding rims to said placing means.

4. An apparatus in accordance with claim 1, wherein said moulds comprise rims movably carried upon opposed edges of the bottom plates.

5. An apparatus in accordance with claim 4, having means limiting the extent of movement of said rims upon said opposed edges.

6. An apparatus for manufacturing light weight building boards comprising, a pressing device for receiving and stacking, one on top of the other, a plurality of moulds each filled with the material of a light weight building board fed to said pressing device from the bottom of said stack, a first rigid frame on said pressing device, a second rigid frame on said pressing device spaced from said first rigid frame for receiving a mould filled with the material of a light weight building board therebetween, a first plate movably mounted on said first rigid frame, a second plate movably mounted on said second rigid frame, drive means articulately connecting said first and second plates

60 to said first and second rigid frames for moving said plates in a horizontal direction toward and away from each other for supporting and releasing said plurality of moulds in said pressing device, and means under said pressing device and said moulds stacked therein and under said plates for receiving a mould filled with the material of a light weight building board and for lifting said received mould toward the bottom of the lowermost mould in said pressing device and for compressing the material of a light weight building board on said receiving mould

65 against the bottom of said lowermost mould, means movable in a horizontal direction toward each other for pushing compressed material of a light weight building board projecting horizontally outward on said receiving mould into said mould, said means under said pressing device

including means for lifting said received mould into contact with the lowermost mould in said stack when said plates are moved in a horizontal direction away from each other.

7. In an apparatus as recited in claim 6 in which said moulds have rims fixed at opposite sides of said moulds and said material of a light weight building board is in said moulds between said rims.

8. In an apparatus as recited in claim 6 in which said moulds stacked in said pressing device have removable rims at the opposite sides of said moulds.

9. In an apparatus as recited in claim 8 in which a rim supplying magazine is positioned on each of said rigid frames and means on said magazine for feeding a rim from said magazines to the side of said received mould when said received mould is lifted by said receiving and lifting means.
